KNITTED FABRIC

Henry Harold Holmes and John Cyril Herbert
Hurd, Leicester, England, assignors to Wildt and
Company Limited, Leicester, England, a British
company

Application December 14, 1939, Serial No. 309,282
In Great Britain December 20, 1938

9 Claims. (Cl. 66—201)

This invention consists of improvements in or relating to knitted fabric and has reference more particularly to knitted fabric which includes purl stitch areas or effects.

The present invention has for its object to provide a knitted fabric of an improved patterned or fancy character as will be hereinafter described.

Broadly considered the invention consists of a knitted fabric wherein pattern effects are produced by purl stitch effects and embroidery plating, such for example as lap or wrap striping effects.

The invention provides a patterned or fancy fabric which as regards the combination of purl stitch effects and embroidery plating as aforesaid is believed to be novel in the art of knitting.

The purl stitch effects may be in the form of solid or hollow blocks, stripes, panels, bands or the like or any desired combination of these, or may form broken designs.

Alternatively, the purl stitch effects may be in the nature of jacquard purl designs, the character of which is well understood by those skilled in the art of knitting.

In the accompanying drawings:

Figure 1 is a greatly magnified view illustrating the front face of a representative portion of the improved fabric.

Figure 2 purports to show in diagrammatic fashion a specimen of fabric knitted in the piece.

Figure 3 illustrates a garment made of fabric embodying plain areas, purl stitch effects and embroidery plating which are distributed differently from the corresponding effects embodied in the fabric shown in Figure 1, and

Figure 4 is a diagram showing knitted articles of the improved patterned or fancy character produced in string formation.

Like parts are designated by similar reference characters throughout the drawings.

In the typical example of the invention illustrated in Figure 1 lap or wrap striping effects A are located in areas B composed of plain stitches 1 surrounding areas C composed of purl stitches 2. The portion of fabric shown is knitted from a main yarn which latter, for convenience in illustration, is left unshaded, and from continuous lap or wrap striping or embroidery threads 3 which are incorporated in predetermined needle wales such as those indicated at w. With a view to emphasizing the lap or wrap striping effects A in Figure 1 the threads 3 are shaded. Wherever the main yarn and the threads 3 are intermeshed, only the latter show on the face of the fabric. Thus, in this particular example, the lap or wrap striping or embroidery threads 3 are intermeshed with predetermined plain stitches 1 at points such as those marked 4; consequently at these points there is embroidery plating, the threads

3 elsewhere extending walewise mainly at the back of the fabric in the form of floats 3a. It is convenient to mention here that instead of the plain areas B surrounding the areas C composed of purl stitches 2 the reverse may be the case, that is to say areas B may be surrounded by areas C.

A few of the many possible distributions of the plain areas, purl stitch effects and embroidery plating are shown diagrammatically in Figures 2-4 and will now be considered.

Thus, in Figure 2, some of the areas composed of purl stitches are in the form of solid squares C¹ while others C² of said areas are solid and of oblong formation. The purl stitch areas C¹ and C² are surrounded by plain areas B, and lap or wrap striping effects A are located in desired plain areas. Conveniently, coursewise extending rows of the squares C¹ alternate with similar rows of the oblong formations C², the latter being staggered with respect to the squares. The effects A may, as shown, consist of zig-zag lines of embroidery stitches and are produced in such of the areas B as alternate with squares C¹ in the direction of the courses. Instead of being rectangular the purl stitch areas may be in the form of diamonds, rings or the like.

Referring to Figure 3, the somewhat narrow purl stitch areas C³ extend walewise of the fabric and are of the general configuration shown. The lap or wrap striping effects A are produced in the plain areas B and consist of rows of hollow diamonds disposed point to point. The remainder of the body portion of the fabric is plain knitted. The rows of diamonds also extend walewise and alternate with the areas C³.

The fabric shown in Figure 4 is patterned by bands C⁴ which are composed of purl stitches and alternate with similar bands B¹ composed of plain stitches, lap or wrap striping effects A in the form of spaced pairs of zig-zag lines of embroidery stitches being produced in said plain stitch bands.

Alternatively, the areas composed of purl stitches may be in the form of hollow squares or diamonds, rings or the like, enclosing correspondingly shaped hollow or solid areas containing lap or wrap striping effects, and when the plain areas are hollow these may likewise enclose other areas composed of purl stitches. Or the reverse formation may be the case, that is, areas composed of plain stitches may enclose areas composed of purl stitches and, if hollow, the latter may enclose other areas composed of plain stitches, in which event either the inner or the outer, or both the inner and outer plain areas may contain lap or wrap striping effects.

From the foregoing it will be apparent that the lap or wrap striping effects may be formed by individual stitches or groups or blocks of

stitches which may be of any suitable shape or form according to requirements.

As will be understood, moreover, many and diverse effects or different combinations of the character aforesaid may be obtained by appropriate production of purl stitches or/and plain stitches and embroidery stitches in desired wales and courses of the knitted fabric. If desired, the patterned or fancy effect may be made more pronounced or enhanced by yarn colour changes, the use of which is well understood in the art.

The invention is applicable to knitted fabric, flat or tubular, knitted in the piece, i. e. in a continuous manner, intended to be cut up subsequently for manufacture into garments such as pullovers, slipovers, jumpers, jackets and like outerwear. A portion of fabric knitted in this manner is represented in Figure 2. The invention is also applicable to lengths of fabric knitted in string formation and joined by separating or parting courses or/and draw threads so as to enable them to be readily separated. Within its scope, moreover, the invention includes knitted articles, such as slipovers, pullovers, jumpers, stockings, half-hose, socks or the like knitted separately; and also articles, or garment lengths such, for instance, as those designated by the reference numerals 5 in Figure 4 produced in string formation with separating or parting courses or/and with draw threads at the locations marked 7 as and for the purpose aforesaid. Accordingly, the expression "knitted fabric" is to be regarded as including garment lengths or articles as well as fabric knitted in a continuous manner.

The invention is also to be regarded as including knitted fabric of the patterned or fancy character hereinbefore set forth comprising a welt 8, a rib knitted course, or courses such as may form the ribbed waist band such as that indicated at 9 of a slipover, pullover or jumper or the ribbed top of a stocking, half-hose or sock, and a main portion with purl stitch effects and lap or wrap striping effects as aforesaid, produced in longitudinal sequence. In this connection the rib knitted course or courses may be of ordinary rib, such as of 1/1, or 2/2 combination, or when there are several courses the ribbed portion produced may be of any desired fancy character. When, as shown in Figure 4, such fabric is produced in the form of garment lengths 5 or articles in string formation with repetition of the sequence aforesaid and with a separating or parting course or draw thread between the welt 8 of one length or article and the main portion of the next, a finished edge is produced at one end of each garment length or article when the said lengths or articles are separated by removal of the separating or parting courses or the draw threads. Conveniently, and as shown, a few waste courses 6 of, say, purl stitches including a separating or parting course or/and the draw thread 7 may be provided between adjacent garment lengths or articles. The specific article shown in Figure 3, by way of example, purports to be a pullover and, as will be seen, this comprises a welt 8, a ribbed waist band 9 (e. g. of 2/2 rib combination), and a main body portion 10 with purl stitch effects C³ and lap or wrap striping effects A distributed as hereinbefore described. The body portion 10 is 70 appropriately finished off with a neck opening 11.

From the foregoing it will be perceived that the invention includes as features flat or tubular knitted fabric of the patterned or fancy character

described produced in continuous manner, flat or tubular garment lengths or articles of the patterned or fancy character described produced in string formation with separating or parting courses or draw threads, with or without rib knitted courses or portions and with or without welts, and a flat or tubular garment length or article of the patterned or fancy character described with or without a rib knitted course or courses and with or without a welt.

What we claim then is:

1. Knitted fabric comprising areas composed of plain stitches, purl knitted portions which are interspersed with the plain stitch areas, and, within said plain stitch areas, patterning produced by lap striping effects.

2. Knitted fabric comprising areas composed of plain stitches, at least some of said areas having therein patterning produced by lap striping effects which are incorporated in desired wales and courses, and purl knitted portions which are interspersed with and surrounded by said plain stitch areas.

25 3. Knitted fabric comprising areas composed of plain stitches, at least some of said areas having therein patterning produced by lap striping effects which are incorporated in desired wales and courses, and purl knitted portions in the form of solid blocks which are interspersed with and surrounded by said plain stitch areas.

30 4. Knitted fabric comprising areas composed of plain stitches, at least some of said areas having therein patterning produced by lap striping effects incorporated in desired wales and courses, and purl knitted portions in the form of stripes which are interspersed with said plain stitch areas.

45 5. Knitted fabric comprising areas composed of plain stitches, at least some of said areas having therein patterning produced by lap striping effects which are incorporated in desired wales and courses, and purl knitted portions in the form of coursewise extending bands which are interspersed with and separated by said plain stitch areas.

60 6. Knitted fabric comprising areas composed of plain stitches, at least some of said areas having therein patterning produced by lap striping effects which are incorporated in desired wales and courses, and narrow, walewise extending purl knitted portions interspersed with and separated by the plain stitch areas.

7. Garment lengths of knitted fabric including areas composed of plain stitches, at least some of said areas having therein patterning produced by lap striping effects incorporated in desired wales and courses, and purl knitted portions which are interspersed with the plain stitch areas, said lengths being separably connected end to end.

55 8. An article which is made of knitted fabric comprising areas composed of plain stitches, at least some of said areas having therein patterning produced by lap striping effects incorporated in desired wales and courses, and purl knitted portions which are interspersed with the plain stitch areas.

65 9. Knitted fabric comprising courses composed of plain stitches, other courses composed of purl stitches said other courses being interspersed with said plain stitch courses, and, incorporated within the latter, patterning produced by lap striping effects.

HENRY HAROLD HOLMES,
JOHN CYRIL HERBERT HURD.
